UNITED STATES PATENT OFFICE.

JOSEPH P. ANGELL, OF PINE BLUFF, ARKANSAS.

RAILWAY-TRACK.

No. 824,970.

Specification of Letters Patent.

Patented July 3, 1906.

Application filed February 9, 1906. Serial No. 300,290.

To all whom it may concern.

Be it known that I, JOSEPH P. ANGELL, a resident of Pine Bluff, in the county of Jefferson, and in the State of Arkansas, have invented a certain new and useful Improvement in Railway-Tracks; and I do hereby declare that the following is a full, clear, and exact description thereof, reference being had to the accompanying drawings, in which—

- 10 Figure 1 is a cross-section of a railway-track embodying my invention. Fig. 2 is a perspective detail view in cross-section of one of the rails, and Fig. 3 a detail view of a portion of one of the rails.
15 The object of my invention is to provide a construction of railway-track which will combine the valuable qualities of economy of building, durability, and safety, and to these ends my invention consists in the railway-track constructed substantially as herein-after specified and claimed.

The rail that I employ has in cross-section a **T** form, it comprising a main or wheel-engaging member **A**, which is preferably rectangular in cross-section, a centrally-located laterally-extending web **B**, and vertical flanges **C**, that extend in opposite directions from the web **B**, the lower vertical flange **C** when the rail is laid on the ties **D** projecting below the top of the ties and engaging grooves or notches **d** therein provided for the reception of said flanges. The latter therefore constitute securing or anchoring means for the rail and, as will be evident, constitute an amply sufficient means to sustain the rail against lateral thrust. To protect the surfaces of the wood of the ties where the cuts or notches are made, the tie may be waterproofed, and as a further precaution the cuts or notches lined with thin plates or sheets of copper or other material, which will prevent the access of water to the wood. Spiking the rail when desirable or considered necessary is done by providing the web **B** at suitable intervals apart with holes, and spikes **E** are driven therethrough into the tie, which spikes may be considerably lighter than those used in laying the rails of ordinary construction, and the spikes are preferably made with conical heads countersunk in the holes in the web. To anchor the spikes at or near their mid-length, they are enlarged or swelled laterally and the enlargement gradually diminished toward the point of the spike.

At their ends the rails are provided with

longitudinally-extending holes **a** in the main or body portion thereof for the reception of pins **F**, a pin **F** being placed in the holes of abutting rails and extending from one to the other, and thus joining them. Preferably a coil-spring **G** is placed between each end of the pin and the adjacent end of the hole in the rail. To brace or reinforce the rails at the joints, a brace-plate may be used, which, as shown, is in the form of an angle-bar **H**, preferably of a length to extend over three or more ties, upon which it is fastened, and engaging the outer side of the main or wheel-engaging portion of the rail, said brace-plate thus being on the side of the rail opposite that where the vertical flanges **C** are situated. The upper surface or edge of the vertical member of the angle-bar, which is the one against the rail, is inclined or rounded at both ends, so that when the car-wheel passes upon the same it will do so smoothly without any shock or blow.

It will be seen that in the construction of my track no fish-plates with bolts and nuts are employed, and this is important, not only as a matter of economy, but the danger arising from nuts working off the bolts is obviated. The upper vertical flange **C** constitutes a guard which is complete security against derailment. The ballast, as shown in Fig. 1, may be filled in between the rails to a level flush with the tops of the upper vertical flange **C**, (which, it will be observed, extends well above the wheel-engaging surface of the rail,) and the top surface of the ballast is coated or finished off with a waterproof plastic material. It will be apparent that thus constructed the track can be easily maintained in a clean condition and kept in proper condition at a minimum expense.

Such portions of the structure as may be desired may be covered with an antirust compound; but of course it is to be understood that I do not restrict myself to any such details nor to the proportions of the rails or other parts of the structure, as changes in these respects may be made without involving any departure from my invention.

My purpose in providing the spiral springs **G** is to provide for the removal of a rail should it at any time be necessary, the procedure in such a case being as follows: The abutting ends of the rails are raised sufficiently to open the joint to permit the pin to be sawed in two, so that the separate portions of the pin may be removed. In re-

placing the rail both springs are placed in the hole *a* in one of the rails. A plug is then placed in the hole *a* of the other rail, partially filling it, and then a half of the sawed pin is inserted, which will extend from one rail to the other. The provision of holes *a* is also useful for the reception of an explosive to be used for the expulsion of the pin when necessary should it be so tightly lodged in the hole as to not to be readily extracted otherwise.

Having thus described my invention, what I claim is—

1. In a railway-track, a rail comprising a wheel-engaging member, a laterally-extending web therefrom, a vertical flange extending upwardly alongside the wheel-engaging member and situated to act as a wheel-guard, and a vertical tie-engaging flange on the web.
- 15 2. A railway-track, comprising rails and

pins in abutting ends of the rails and elastic 20 pin-engaging means.

3. A railway-track, comprising rails consisting of a wheel-engaging member, and vertical flanges, one of which is an anchoring-flange and the other a wheel-guard, and pins 25 in openings in abutting ends of the rails.

4. A railway-track, comprising rails consisting of wheel-engaging members, vertical flanges, one of which is an anchoring-flange, and the other a wheel-guard, and ballast in 30 the space between the flanges of opposite rails.

In testimony that I claim the foregoing I have hereunto set my hand.

JOSEPH P. ANGELL.
